SUDSER FOR A FOUNTAIN BRUSH

Leonard Osrow, Great Neck, and Harold Osrow,
Roslyn, N.Y.

Application January 8, 1959, Serial No. 54,079

Term of patent 7 years

(Cl. D9—2)

Fig. 1.

Fig. 2.

Fig. 3.

Fig. 5.

Fig. 4.

Fig. 1 is a side elevational view of a sudser for a fountain brush showing our new design, with the portion of a fountain brush shown in dotted lines for illustrative purposes only;

Fig. 2 is an enlarged top view of the sudser;

Fig. 3 is a side elevational view of the sudser;

Fig. 4 is an elevational view of one end of the sudser; and

Fig. 5 is an elevational view of the other end of the sudser.

We claim:

The ornamental design for a sudser for a fountain brush, substantially as shown and described.
